WILHELM KASTERT, OF MULHEIM-RUHR, GERMANY, ASSIGNOR TO SIEMENS-SCHUC-KERTWERKE AKTIENGESELLSCHAFT, OF BERLIN-SIEMENSSTADT, GERMANY, A CORPORATION OF GERMANY

METHOD OF MANUFACTURE OF BLADE DISKS FOR RADIAL ADMISSION TURBINES

Application filed January 17, 1930, Serial No. 421,438, and in Germany January 18, 1929.

My invention relates to improvements in the method of manufacture of blade assemblies for radial admission turbines.

- My invention consists substantially in providing flat bars or strips with slots along one edge of each, in inserting the opposite ends of individual blades into these slots with said bars or strips arranged in a common plane and with the widths of said blades arranged transversely with respect to said common plane. Said blades are then metallically joined to the side bars or strips after which the blading section thus constructed is subjected to a machining operation followed by an arcuate bending operation to prepare them for being parallelly mounted in the axially presented flanges of the rotor or stator member of the turbine with which they are rigidly united.
- 20 An embodiment of my invention is shown on the annexed drawing in which

Figure 1 is a radial section of the stator body of a radial admission turbine provided with a blading assembly constructed according to the present improved method.

Figure 2 is a corresponding radial section of a rotor disk provided with a blading assembly constructed according to the present invention and coaxially arranged with the stator body in readiness to be moved axially into inter-operative position with respect to said stator body.

Figure 3 is a fragmentary radial section of the rotor disk, having a finished blading section mounted between the axially-spaced carrier and bearing rings for one of the circular blade assemblies.

Figure 4 is a plan view of one of the partly-finished blading sections prior to the machine finishing and cylindrical bending operations which precede the mounting of said section in the rotor disk.

Figure 5 is an edgewise view of Figure 4.

Figure 6 is a plan view of a blank or blade section cut from a rod or stock-piece having the desired cross-section of the finished blade.

Figure 7 is an end view of the same.

Figure 8 is a fragmentary top plan view of a finished blade segment prior to insertion in the rotor or stator.

Figure 9 is a fragmentary section of the same on the line 9-9 of Figure 8.

In the embodiment of my invention shown on the drawing, blading sections of my improved construction are mounted to project axially from suitable stator and rotor bodies prior to their placement into interoperative position. For this purpose, I may employ a stator body 1 provided with a central inlet opening 2 for the admission of steam around the end of a rotor shaft 3 upon which the hub portion 4 of a rotor disk 5 is supported. The stator body 1 is provided with annular recesses 6 which are arranged in groups which decrease in depth toward the axis of the stator. The annular recesses 6 form a plurality of concentrically arranged bearing ledges 7 which carry circular series of stator blades 8, each circular series of said stator blades being arranged intermediately with respect to one of the bearing ledges 7 and a circular bearing ring 9 which is axially displaced with respect to said bearing ledge. The rotor disk 5 is provided with a series of annular recesses 10 forming bearing ledges 11 from which the rotor blades 12 project axially in circumferential series, the rotor blades 12 in each circular series being connected together at their outer ends by a circular bearing ring 13. After the stator and rotor have been constructed in the manner to be hereinafter pointed out, the rotor is moved axially into cooperative relation with the stator body, with the protruding bearing rings 13 on the outer ends of the rotor blades 12 in rotary sliding contact with the corresponding bearing ledges 7 of the stator body 1.

The manufacture of the blades according to my invention takes place in the following manner. From a stock piece or bar which has been drawn with the desired cross-section shown in Figure 7, are cut blades 8 or 12 of the required length. Suitable side bars or strips 14 and 15 which have been cut from flat stock in lengths equal to the rectified arc of the desired arcuate blading section, are provided with slots or notches *c* along one edge of each for receiving the opposite ends of the blades 8 or 12 with their broad sur-

faces or widths arranged transversely to the edges of said side bars or strips. Said blades are then metalically joined to the side bars by welding or soldering at one or both ends to form a kind of lattice work or grid as shown in Figures 4 and 5. This grid or partly-finished blading section is then subjected to a suitable process, such as milling, to impart the desired size and finish thereto and for removing the material enclosed by dotted lines in Figure 3. The blading section is then bent into an arc to conform to the curvature of the ledge or carrier flange which projects axially from the rotor or stator member of the turbine as the case may be. The completed blading section is now ready for installation on the carrier and may be rigidly united thereto by a suitable operation such as rolling.

20 My improved method of manufacture is characterized by great simplicity and economy connected with the assembly of the parts constructed from previously shaped stock and the machining operations performed on 25 an entire blading section instead of on its constituent parts.

I claim:—

1. The process of producing sections of blades for radial flow turbines, which process 30 consists in arranging the individual blades in parallelism with each other and extending between the spaced adjacent edges of two parallelly arranged flat side bars, in joining the opposite ends of said blades to said side bars 35 respectively, and finally in bending the flat blading section thus produced into an arcuate cylindrical form.

2. The process of producing sections of blades for radial flow turbines, which process 40 consists in arranging the individual blades in parallelism with each other and with their opposite ends crosswise with respect to the adjacent edges of two parallelly arranged flat side bars, in uniting the ends of 45 said blades to said side bars to form a flat blading section, and finally in bending said flat blading section into an arcuate cylindrical form.

3. The process of producing sections of 50 blades for radial flow turbines, which process consists in arranging the individual blades in parallelism with each other and with their opposite ends angularly disposed with respect to the adjacent edges of two 55 parallel flat side bars, in uniting the ends of said blades to said side bars, in machining the flat blading section thus produced, and finally in bending said flat section into an arcuate cylindrical form.

60 4. The method of making arcuate cylindrical sections of blading for radial flow turbines, said method consisting in arranging a pair of flat strips with their lateral edges parallel, in cutting blade sections of substantially uniform length from a bar having

the standard cross-section of the finished blades, in arranging said blades in parallelism with each other between the edges of said flat strips with the widths of said blade sections inclined to the common plane of said flat strips, in joining the opposite ends of each blade to the adjacent edges of said flat strips, and in bending the flat strips into cylindrical arcuate form adapted to be concentrically mounted with respect to the rotary axis of said turbine.

5. The method of making arcuate cylindrical sections of blading for radial flow turbines, said method consisting in constructing a pair of flat side strips, in cutting uniformly spaced slots in one edge of each of said side strips, in arranging said side strips parallel to each other with their slotted edges presented towards each other, in inserting the opposite ends of a plurality of parallelly arranged blades in the slots in the adjacent edges of said side strips, said blades being arranged to project edgewise on opposite sides of the lateral strips, in securing the opposite ends of said blades to the side strips, and in bending the blading section thus produced into an arcuate cylindrical form.

6. The method of making arcuate cylindrical sections of blading for radial flow turbines, said method consisting in constructing a pair of side strips of equal length, in cutting uniformly spaced slots in one edge of each of said side strips, in arranging said side strips parallel to each other with their slotted edges adjacent to each other, in cutting sections of substantially uniform length from a bar provided with the standard cross-section of the finished blades, in inserting the opposite ends of each blade into the slots of said side strips, in uniting the ends of said blades to the side strips, and in bending the blading section thus produced into a cylindrical arc.

7. The method of making arcuate cylindrical sections of blading for radial flow turbines, said method consisting in providing one edge of each of a pair of side strips with uniformly spaced slots, in arranging said side strips with their slotted edges parallel and adjacent, in inserting the opposite ends of a plurality of blades into the slots in said side strips, said blades being arranged transversely to the thickness of metal in said side strips, in welding said blades to one of said side strips, in machining the partially-completed blading thus produced to the desired finished form, and in bending the blading section into a cylindrical arc corresponding to the curvature of the carrier in which it is to be mounted.

8. The method of making arcuate cylindrical sections of blading for radial flow turbines, said method consisting in constructing a pair of side strips of equal length, in cutting uniformly spaced slots in one edge

of each of said side strips, said slots having a width approximately equal to the greatest thickness of the blades, in arranging said side strips with their slotted edges parallel and
5 adjacent, in cutting sections of substantially uniform length from a bar of standard cross-section to form the blades, in inserting the opposite ends of said blades into the slots of said side strips with their widths arranged
10 transversely to the thickness of metal composing said side strips, in welding said blades to the side strips, in milling off the opposite ends of the blades to the finished length, in bending the blading section into an arcuate
15 cylindrical section, in inserting the lateral strips and milled portions of the blades into axially spaced slotted carrier flanges of a turbine member, and in deforming the metal in said slotted carrier flanges to positively
20 clamp the arcuate segments in position in the carrier.

In testimony whereof I affix my signature.
WILHELM KASTERT.
